EGG-BOX

Jean Giraudet, Saint-Herblon, and Pierre Giraudet,
Ancenis, France, assignors to Giropor Societe a Respon-
sabilite Limitee Chemin de la Paonnerie, Anetz, Loire
Atlantique, France

Filed Oct. 9, 1970, Ser. No. 25,406

Term of patent 14 years

Int. Cl. D9—03

U.S. Cl. D9—190

FIG. 1

FIG. 2

FIG. 3

FIG. 4

FIG. 5

FIG. 1 is a top, front perspective view of an egg-box showing our new design;

FIG. 2 is a bottom, rear perspective view thereof;

FIG. 3 is a side perspective view thereof in a partially open position;

FIG. 4 is a cross-sectional view along line 4—4 of FIG. 3 but in fully opened position; and

FIG. 5 is a partial section through line 5—5 of FIG. 1. We claim:

The ornamental design for an egg-box, as shown and described.
